SAFETY BATHTUB SEAT

James Francis Gass, 66 E. 83rd St., New York, N.Y.

Tiled July 31, 1961, Ser. No. 128,038

1 Claim. (Cl. 4—185)

This invention relates to bathtub seats and more particularly to a seat adapted to be supported within a tub of the roll rim, built-in or other standard type and suspended from the rim edge of the tub.

A principal object of the invention is to provide a bathtub seat with means for supporting the seat from the rim edge of the tub and also from the side wall of the tub, thus distributing the bearing of the supporting parts upon the tub and obviating the necessity of using hooks or other members caught around the rim of the tub and engaging with the porcelain lining at the edge thereof.

Another object of the invention is to provide a seat for a bathtub that is readily applied to an ordinary bathtub and is readily made to fit the ordinary bathtub.

A further object is to provide a bathtub seat that is adjustable to fit tubs of varying widths, even built-in tubs with a flush wall.

Yet another object is to provide a bathtub seat that is adapted to be positioned on the rim of the ordinary tub and is provided with means for securing the seat in position and for preventing slippage.

A still further object is to provide a bathtub seat that is strong and durable, simple in construction and that may be used in tubs of the finest construction and material without danger of damaging the surfaces thereof at the parts where the seat is applied.

For further comprehension of the invention and of the objects and advantages thereof, reference will be had to the following description and accompanying drawings and to the appended claims in which the various novel features of the invention are more particularly set forth.

In the accompanying drawings forming a material part of this disclosure:

FIG. 1 is a top perspective view of a fragment of a bathtub with a seat embodying the present invention applied thereto.

FIG. 2 is a vertical sectional view taken on the line 2—2 of FIG. 1.

FIG. 3 is a top plan view thereof.

FIG. 4 is a cross-sectional view taken on the line 4—4 of FIG. 3.

FIG. 5 is a cross-sectional view taken on the line 5—5 of FIG. 3.

FIG. 6 is a view similar to FIG. 1 showing a modified form of bathtub seat.

Referring in detail to the drawings, in FIG. 1 an ordinary porcelain bathtub 10 is shown having a flat rim 12. A bathtub seat 14, made in accordance with one form of the invention, is shown in the tub suspended from the rim 12.

The bathtub seat 14 comprises a flat rectangular-shaped smooth wooden panel, constituting a seat 16. At each end, a pair of steel brackets or clamps 18 is secured to the seat by means of pairs of bolt and nut assemblies 20. Each bracket 18 comprises an elongated rectangular-shaped flat strip of metal 22 terminating at one end in a flat flange disposed at right angles to the plane of the strip and extending in one direction and constituting a supporting arm 24. The strip terminates at its other end in a similar flat flange disposed at right angles to the plane of the strip and extending in the opposite direction and constituting a supporting arm 26. The arm 26 is formed with a pair of smooth-walled holes 28. Each assembly 20 comprises a pair of threaded bolts 30 each formed with a head 32 and adjacent noncircular shank

2

portion 34, the remainder of the bolt being threaded. The bolts 30 extend through smooth-walled openings 36 formed in the ends of the seat 16 and through the aligned smooth-walled openings 28 in the arms 26 of the brackets. 5 Nuts 38 on the protruding ends of the bolts secure the brackets to the seat and washers 40 are interposed between the nuts and arms 26.

A strip of nonslippping material such as rubber is secured to the inner surfaces of the strip 22 and arm 24, said strips constituting linings 42. The linings are formed with corrugations 44 to enhance the gripping action thereof. The linings prevent the brackets from slipping on the porcelain of the tub and also protect the porcelain surfaces from damage by the seat.

10 Additional means is also provided to prevent slippage of the brackets and seat and to afford adjustment whereby the seat is adapted to fit varying sizes of tubs and also fit built-in tubs with a flush wall. This means comprises a screw 48 supported horizontally by means of an angular bracket 50 secured to one end of the seat 16 at its center by bolt and nut assemblies similar to the bolt and nut assemblies 20 securing the brackets 22 to the seat. The screw 48 extends through a threaded hole 52 in the bracket 50 and carried on one end thereof is a rubber 15 cup or washer 54 adapted to contact the side wall of the tub. On the other end of the screw there is a roughened finger piece 56 for manipulating the screw. Upon setting up on the screw the cup or washer frictionally engages the wall of the tub thereby preventing slippage and assisting the arms 24 and strips 22 in supporting the seat. Furthermore, the screw will take up any clearance between the seat 16 and side wall of the tub thereby accommodating the seat to various widths of tubs.

20 In the use of the seat, the weight is borne entirely upon the cushion linings 42, and these linings are supported upon the porcelain or enameled surfaces of the tub away from any edge portions thereof, thus guarding against cracking, peeling or otherwise damaging the surface.

25 In FIG. 6, a modified form of bathtub seat 14' is shown. This form differs from the seat 14 merely in providing a backrest 50' for the user of the seat. The backrest 50 includes an L-shaped bracket 52', the horizontal arm of which, as viewed in FIG. 6, is fastened to the underside 30 of the seat 16' by bolt and nut assemblies similar to the bolt and nut assemblies 20. A rectangular-shaped board 54' is suitably fastened to and across the top end of the vertical arm 52' of the bracket 52'. The board is disposed vertically in substantially the plane of the adjacent long edge of the seat 16' so that the back of the user may engage the same for support.

35 While I have illustrated and described the preferred embodiments of my invention, it is to be understood that I do not limit myself to the precise constructions herein disclosed and that various changes and modifications may be made within the scope of the invention as defined in the appended claim.

40 Having thus described my invention, what I claim as new, and desire to secure by United States Letters Patent is:

45 A bathtub seat comprising a rectangular-shaped flat wooden panel constituting a seat, said panel having holes at its ends, spaced angular supporting brackets connected to the ends of the panel and extending angularly and outwardly of the ends, said angular brackets having holes adjacent one end thereof in line with the holes in the panel, said connection including bolt and nut assemblies 50 extending through the holes in the panel and brackets, corrugated strips of rubber on the surfaces of the protruding portions of the brackets to prevent slippage of the brackets and panel, an angular bracket secured to one

end of the panel between the first-named brackets, said latter angular bracket having a threaded opening in one end thereof, a screw member extending through said opening, a rubber cup on one end of the screw member for engaging the wall of a bathtub, a finger piece on the other end of the screw member, an L-shaped bracket having one end secured to a long edge of said panel, said bracket having an arm extending vertically perpendicular to the panel, and a board secured to the upper free end of the arm to serve as a backrest.
